Primary Examiner — Jennifer L Rempfer

(57) CLAIM

The ornamental design for a pillow, as shown and described.

DESCRIPTION

FIG. 1 is a perspective view of a pillow showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the pillow showing my new design where the pillow is in a first configuration of use; and, FIG. 10 is a perspective view of the pillow where the pillow is in a second configuration of use.

The broken lines in the drawings depict portions of the pillow that form no part of the claimed design.
